Claims priority, application Switzerland July 20, 1961
2 Claims. (Cl. 102—38)

This invention relates to a projectile.

Various means have already been proposed for the purpose of attenuating the noise of firearms, reducing the muzzle flash and diminishing the visibility of the smoke (silencers, flash-concealers, special smokeless powders). But hitherto, none of the means proposed completely and wholly obviates all these three phenomena, which usually accompany the firing of projectiles.

It is an object of the present invention to produce a projectile whose construction enables it to be propelled by means of a pyrotechnic charge, simultaneously without appreciable noise, without flash and without smoke.

According to the present invention there is provided a projectile, wherein the projectile has at least two elements adapted to move relative to one another over a certain length limited by retaining means which are adapted to render the elements effectively integral with one another at the limit of stroke, the two elements serving to confine an expansion chamber which contains a launching charge and the volume of which varies when the launching charge is fired by virtue of the relative movement of the two elements, and wherein one of said elements is rigidly secured to the projectile, while the other is arranged to be acted on by a firing device for firing the projectile and to be removed from the firing device by the projectile and the element secured thereto when the two elements have reached their limit positions and are effectively integral with one another due to the action of said retaining means.

Preferably, the expansion chamber is hermetically sealed during the propulsion and whilst travelling along the trajectory.

As a result of the aforesaid arrangements, the gases produced by the propulsive charge expand, when the shot is fired in the said chamber, remain confined in the latter and do not come into contact with the atmosphere, so that the shock wave of the launching charge is not audible, and so that the flames and smoke produced by the combustion of the powder are carried off by the projectile without causing any apparent phenomenon at the muzzle of the weapon.

If the expansion chamber is sealed, a residual pressure is preserved in the interior thereof. If on the contrary the said chamber is not entirely hermetically sealed, the gases are able to flow through the interstices accessible to them. Since the said interstices are assumed to be small, the flow permitted by them is small, and in this case again the launching of the projectile is not accompanied by any appreciable noise.

The present projectile provides its user with certain tactical advantages, and makes it possible to launch a projectile without the enemy being able to localise the firing of the shot by any visible or audible phenomenon, thereby to increase the firer's security and to produce an effect of surprise upon the enemy.

In one embodiment of the projectile, the element which is arranged to be acted on by the firing device is a piston arranged inside the other element, which constitutes a guiding cylinder for the said piston.

The retaining means for the piston in the cylinder may comprise a reduced portion at the rear of the cylinder against which the piston is arrested at the end of propul-

2

sion. The said reduced portion may be internally truncated and prolonged, if appropriate, at its free end by a cylindrical portion of sufficient length for the purpose of centering the firing device. The said cylindrical portion may further comprise, externally, a stabilising empennage.

According to another embodiment, at least one of the two aforesaid elements is provided with a shock absorber which is struck by the other element at the limit of stroke.

10 Preferably, the shock absorber is constructed of a non-metallic elastic or plastic material, or alternatively of a metal adapted to undergo a progressive deformation without rupture.

In one constructional variant of the projectile the shock absorber is a deformable annulus surrounding the said piston, and in another constructional variant, the shock absorber is constituted by an assembly of fins of circular shape superimposed on one another in planes normal to the axis of the piston, and axially deformable.

15 In a third variant, the shock absorber is constituted by a stack of elastic washers of the type known as "Belle-ville," intended to constitute a progressive braking spring, and in yet another variant, the shock absorber is constituted by a succession of washers, the external peripheries of which form projections intended to be bent upon contact with a stop element.

20 In order to effect sealing of the expansion chamber, one of the elements may comprise a sealing means adapted to form a joint with the other element.

25 In one specific embodiment, the launching charge is housed in a receptacle constructed in the interior of the element or piston which is arranged to be acted on by the firing device. According to a variant, the said charge is retained in the interior of a cartridge independent of the said element or piston.

30 The firing device may comprise a striker rod adapted to slide in a strong tube, against the rear of which the piston is supported during the propulsion. The piston may also be provided at its base with a centering housing in which the said tube engages.

35 In order to reduce the recoil stroke of the firing device and to enable it to be anchored, the latter may comprise at its base a solid part provided with projecting portions adapted to bite into the ground when the shot is fired.

40 In the various embodiments of the present projectile the element which is arranged to be acted on by the firing device comprises at its base a detonator intended to set fire electrically or mechanically to the launching charge.

45 Whatever the principle of operation of the detonator may be, the latter is preferably mounted on a strong seat so as to withstand the internal pressure of the gases produced in the expansion chamber.

50 In order to perfect the sealing of the expansion chamber, the element which is arranged to be acted on by the firing device may comprise, behind and in the vicinity of the said detonator, a striker which can function as a valve if the floor of the detonator is burst by the launching charge. When the shot is fired, the striker may be projected onto the detonator in known manner by the pressure of the gases emanating from a small additional cartridge.

55 In another embodiment, the projectile comprises two telescopic tubular elements nested in one another before the shot is fired, while the element which is arranged to be acted on by the firing device projects behind the other element and constitutes the rear portion of the empennage-carrying tail of the projectile. The said tail may be arranged either inside or outside the other element, which is itself integral with the projectile.

60 In order to enable the invention to be more readily understood, reference will now be made to the accom-
65
70

panying drawings which show diagrammatically and by way of example some embodiments thereof, and in which:

FIGS. 1 and 2 show in longitudinal section a first form of construction of a projectile, before and after firing respectively.

FIGS. 3 and 4 show, in longitudinal section and in the same positions, a portion of a second form of construction of a projectile.

FIG. 5 is a partial view in longitudinal section of a modification of the embodiment shown in FIGS. 3 and 4. 10

FIGS. 6 and 7 show schematically, likewise in longitudinal section, portions of two other forms of construction of the projectile, and

FIGS. 8 and 9 show schematically and partially, two further modifications of the embodiment shown in FIG. 1. 15

Referring now to FIGS. 1 and 2, there is shown a projectile comprising a charge-carrying body formed by a casing 1 containing an offensive charge 2 (which may be an explosive, incendiary, smoke-producing, or other charge) which is capable of being ignited by means of a fuze 3 fastened at the head of the casing 1. A tubular tail 4 is screwed into the rear of the casing 1 and has a forward portion 4a which extends inside the charge carrying body, the forward end of the portion 4a being sealed by a plug 5 and being isolated from the charge by a protective casing 6. At its rear end, the tail 4 carries an empennage, the fins 7 of which are integral with a mouthpiece 8 which is screwed onto the terminal portion of the tail and the interior of which is formed as a tapered throat 8a constricting the aperture of the tail. The aperture has a series of longitudinal grooves 8b by means of which the chamber contained in the interior of the tail 4 is in communication with the exterior of the projectile in order to avoid any increase in pressure in the said chamber during the propulsion. The tail 4 also encloses a piston 9 comprising a detonator 10, a propulsive charge 11 for the projectile and a shock absorber element formed by an annular lining 12 of a non-metallic synthetic resin or plastic material, or alternatively of a ductile metal—for example, lead. A toroidal seal 13 housed in an annular recess in the piston 9 serves to seal the chamber contained between the latter and the plug 5.

FIG. 1 shows the projectile housed in a packing therefore, such packing comprising a cylindrical case 14 acting as launching support, a forward cover 15 and a base cover 16, the forward cover and base cover being intended to be withdrawn at the moment of firing. The case 14 is integral with a firing device comprising a base 17 and a tubular sleeve 18 one end of which is axially engaged in the piston 9 and the other end of which is screwed into the base 17, which has a peripheral annular part 17a on which the rear end of the case 14 is secured by forcing, sticking or otherwise. The base 17 also comprises a series of projecting parts 17b intended to effect anchorage of the device in the ground when the shot is fired. The firing device also includes a striker rod 19 guided axially inside the sleeve 18, said rod being retained in a safety position by a pin 21 counteracting a spring 20 which normally urges the rod in the forward direction.

Firing of the shot is effected by tearing away the said pin 21, whereupon the rod 19, being released, strikes the detonator 10 and causes ignition of the propulsive charge 11 contained in the piston 9. The expansion of the gases in the chamber formed inside the tail 4 brings about propulsion of the projectile, which moves with reference to the piston 9, which is supported against the rear section of the firing device, which is itself anchored in the ground and which undergoes the recoil effect. When the piston 9 reaches the end of the expansion chamber, the lining 12 becomes progressively crushed onto the conical throat 8a and effects hermetic sealing of the said chamber, the piston 9 being then rendered integral with the tail 4 and becoming detached from the sleeve 18 (FIG. 2).

The base of the casing which surrounds the detonator 10 is strong so as not to be perforated at the percussion. 75

After explosion of the propulsive charge, the said casing remains integral with the piston and blocks the fire transmission channel. The gas expansion chamber is consequently hermetically sealed during the propulsion phase of the projectile and throughout its travel along its trajectory. The gases remain confined in the said chamber and do not come into contact with the atmosphere, so that the shock wave emanating from the launching charge when the shot is fired is not audible, and so that the flames and smoke produced by the combustion of the powder are carried away by the projectile in the said chamber without producing any apparent phenomenon.

The embodiment illustrated in FIGS. 3 and 4 shows a projectile—for example, a rifle grenade—which is launched by means of a launching sleeve secured to the end of a firearm. The warhead 22 of the projectile (partially shown) comprises at its rear a tubular tail 23 terminated by mouthpiece 24 bearing the fins 25 of a stabilising empennage. The mouthpiece 24 is formed internally with a conical throat 24a which constricts the aperture of the tail, in which aperture a launching sleeve 26, maintained at the end of the barrel of a rifle (not shown), can be engaged. The end of the sleeve 26 is surmounted before firing by the rear portion of a piston 27 which has at its other end a perforated annular wall 27a forming the housing for a propulsive charge 28. In an axial chamber in the piston 27 there is secured a bushing 29 constituting the seat of a striker 30 intended to effect ignition of a detonator 31 retained between the base of the said chamber and the end of the bushing 29. The striker 30 is secured in its pre-firing position on the bushing 29 by a crimping collar 30a.

The piston 27 comprises a series of annular fins 32 superimposed on one another in planes normal to the axis of the projectile, and constituting the shock absorber element of the said piston when the latter comes into contact with the conical throat 24a, the fins being such as to be capable of being progressively crushed against the said throat and to effect sealing of the expansion chamber.

When the shot is fired, the firer actuates the trigger and ignites a small charge of powder housed in a special cartridge (not shown) with which the rifle is loaded. The pressure of the gases emanating from the said cartridge is sufficient to deform the collar 30a and to bring about the release of the striker 30 which is thrown against the detonator 31, causing ignition of the propulsive charge 28, the base of the detonator 31, which has not been perforated by the percussion, remaining integral with the piston and effecting closure of the said expansion chamber.

As with the embodiment described with reference to FIGS. 1 and 2, the projectile is propelled by the expansion of the gases and pressure of which is exerted upon the base of the expansion chamber formed inside the tail 23, whereas the piston 27 is supported against the end of the sleeve 26. When the throat 24a comes into contact with the said piston, the fins 32 are progressively crushed against the tapered surface of the said throat and enable the shock produced by that contact to be deadened for a certain stroke distance. The clamping of the piston 27 in the mouthpiece 24 likewise permits sealing closure of the expansion chamber to be achieved (FIG. 4).

FIG. 5 shows a constructional variant of the projectile described with reference to FIGS. 3 and 4. The launching device, similar to that shown in FIGS. 1 and 2, is constituted by a tubular sleeve 33 in which is guided a striker rod 34 intended to effect ignition of a detonator 35 integral with a piston 36. A propulsive charge 37 is contained in a perforated cartridge 38 which is independent of the piston 36 but integral with the base of the expansion chamber—that is to say, with the rear wall 39 of the warhead of the projectile, onto which a tail 40 is screwed. An annular sealing element 41 of

inverted U-shape in cross-section is intended to prevent any escape of gases towards the warhead of the projectile. The piston 36 likewise possesses an assembly of fins 42 adapted to be crushed against a conical throat at the limit of stroke and to produce the effects described hereinbefore.

The two embodiments shown schematically in FIGS. 6 and 7 relate to projectiles intended to be fired by means of firearms firing at high angles of elevation—for example, a mortar (not shown). They both possess a tail comprising two telescopic elements, one of which is intended to move with reference to the other when the shot is fired, by the action of the pressure of the gases emanating from the propulsive cartridge.

In FIG. 6, the warhead of the projectile bears a tubular tail 43 possessing at its rear a reduced part preceded by a conical throat 43a. A tubular element 44 is mounted for sliding inside the tail and is provided at its rear with a stabilizing empennage 45 and a propulsive cartridge 46 and, at its front with an enlarged part having the internal diameter of the tail 43 and preceded by a conical throat 44a parallel to the throat 43a of the tail. The tubular element 44 is further provided with an annular lining 47—for example, of flexible substance—constituting the shock absorbing element defined hereinabove.

In the embodiment shown in FIG. 7, the warhead of the projectile is integral with a tubular element 49 which is surmounted by an empennage-carrying tail 50. The tail 50 carries at its rear end a propulsive cartridge 46 and a detonator 48, and at its front end an annular lining 47 intended to be crushed against a tapered throat 49a of the element 49.

At the instant of firing, the projectile is introduced into the muzzle of the weapon, so that the detonator 48 encounters a striker with which the latter is provided and effects ignition of the propulsive cartridge 46, which comprises a deformable element which is not perforated upon percussion and which, since it remains integral with the tail throughout the expansion of the gases, blocks the aperture of the latter. The expansion of the gases brings about propulsion of the projectile, the tail 43 (or the element 49 respectively) until the lining 47 comes into contact with the conical throat 43a (or the conical throat 49a respectively). Since the gas expansion chamber remains hermetically closed throughout the travel of the projectile in the weapon and along its trajectory, the gases remain confined in the said chamber and do not expand in the gun barrel. Since the flames and smoke produced by the combustion of the powder are carried away by the projectile, no noticeable effect such as would enable the firing position to be discovered is produced at the muzzle of the weapon.

In the embodiment shown in FIG. 8, a piston 51 is equipped with elastic trunco-conical washers 53 of the "Belleville" type, stacked so as to form a spring which, by its contact with a stop element 54, brakes and then arrests the piston 51 when the projectile is fired in the manner indicated above.

In the embodiment shown in FIG. 9, a piston 55 is equipped with washers 56 whose peripheries form projections which are intended to be bent upon contact with a stop element 57 when the projectile is fired in the manner indicated above, the bending of the projections bringing about progressive braking of the piston 55.

In another modification (not shown) of the projectile shown in FIG. 1, the empennage 7 could be fastened directly onto the cylindrical tail 4 instead of being fixed onto the retaining element 8, while the grooves 8b may be formed on the sleeve 18 instead of in the aperture of the throat 8a.

I claim:

1. A projectile comprising a casing, a tubular tail with its front portion fixed solidly to the rear of said casing, the rear part of said tail having a smaller inside diameter than the corresponding inside diameter of said front portion, a tubular piston inside said tail, a rearward portion in said piston at the rear of said tail, said piston having a front end with an outer diameter corresponding to the inner diameter of said front portion, a stabilizing empennage mounted around the rearward portion of said piston, a longitudinal expansion chamber in said tubular piston, a propulsive cartridge inside said chamber and closing means around said piston for hermetically closing said expansion chamber during the travel along all the trajectory of said projectile.

2. A projectile comprising a casing, a tubular element integral with said casing, said tubular element being open at its rear end, an external flaring throat around said end, a tubular tail surrounding said tubular element, a stabilizing empennage solid with said tail, said tubular element constituting a piston slideable inside said tail, the front inner diameter of said tail being smaller than the outer diameter of said throat, an expansion chamber in said tubular element, a propulsive cartridge inside said chamber and closing means at the rear of said tail and between said tail and said tubular element for hermetically closing said expansion chamber during the travel along all the trajectory of said projectile.
